Primary Examiner — Susan Bennett Hattan*Assistant Examiner* — Marie Fast Horse(74) *Attorney, Agent, or Firm* — Maginot, Moore & Beck, LLP(57) **CLAIM**

The ornamental design for sound reproduction equipment, as shown and described.

DESCRIPTION

FIG. 1 is a perspective view of sound reproduction equipment showing my new design;

FIG. 2 is a right side elevational view showing the design for the sound reproduction equipment of FIG. 1;

FIG. 3 is a left side elevational view showing the design for the sound reproduction equipment of FIG. 1;

FIG. 4 is a front elevational view showing the design for the sound reproduction equipment of FIG. 1;

FIG. 5 is a rear elevational view showing the design for the sound reproduction equipment of FIG. 1;

FIG. 6 is a top elevational view showing the design for the sound reproduction equipment of FIG. 1; and,

FIG. 7 is a bottom elevational view showing the design for the sound reproduction equipment of FIG. 1.

The broken line showing of portions of the sound reproduction equipment in the drawings is included for illustrative purposes only and forms no part of the claimed design.
